UNITED STATES PATENT OFFICE.

WEBB JAY, OF CHICAGO, ILLINOIS.

VACUUM FUEL-FEED DEVICE FOR INTERNAL-COMBUSTION ENGINES.

1,295,036.

Specification of Letters Patent.

Patented Feb. 18, 1919.

Application filed January 2, 1918. Serial No. 209,871.

To all whom it may concern:

Be it known that I, WEBB JAY, a citizen of the United States, residing at Chicago, in the county of Cook and State of Illinois, 5 have invented certain new and useful Improvements in Vacuum Fuel-Feed Devices for Internal-Combustion Engines, of which the following is a specification, reference being had to the accompanying drawings, 10 forming a part thereof.

The purpose of this invention is to provide an improved means for effecting so-called vacuum feed of the fuel to an automobile engine, and incidentally effecting 15 aeration of the cooling water of the engine. It consists in the elements and features of construction shown and described, as indicated in the claims.

In the drawings:

20 Fig. 1 is a side elevation of an automobile engine equipped with this device, the same being shown in connection with portions of the chassis or frame structure of an automobile.

25 Fig. 2 is an enlarged view of the feed device shown in Fig. 1, being partly in vertical section to show the working parts, together with a diagrammatically appended detail of a suction producing device.

30 Fig. 3 is a detail elevation of an oil circulating pump, showing in section a suction producing device associated therewith.

In the drawings there is shown an automobile engine in its customary position on 35 the chassis of the automobile, such engine having the customary jacket for the cooling water shown at 1, and radiator at 2, together with a pipe 3, and circulating pump, 4, forming a part of the cooling water circulatory

40 system. Upon the engine in customary position there is shown a vacuum fuel feed device, 5, of familiar form, comprising the vacuum chamber, 6, to which a pipe, 7, leads from the main low level fuel supply tank, 8, shown in customary position at the rear 45 of the automobile chassis. The specific purpose of the present invention is, as to the vacuum fuel feed device, to provide a novel means of producing the partial vacuum by

50 which the fuel is lifted from the low level tank to the higher feed tank. This expedient, in its usually preferred form, consists in providing in the cooling water circulatory system at some convenient point as, for example, in the pipe, 3, extending between the radiator, 2, and the jacket, 1, a Venturi

throat piece, 10, through whose throat-way the current of cooling water will have a relatively high speed, and connecting into said throat-way at a proper point with respect 60 to the apex thereof, a pipe, 11, which leads from the top of the vacuum chamber, 6, of the elevated fuel feed tank, so that the rapidly moving current of cooling water passing the venturi will entrain air through 65 said air pipe, drawing the same out of the vacuum chamber, producing a partial vacuum therein as desired. For the purpose of rendering this entrainment as effective as possible, it is desirable that the air pipe, 70 11, should extend into the Venturi throat piece and turn therein forward—that is to say, onward in the direction of movement of the cooling water therethrough, being open for such entrainment at a point beyond 75 said apex in the direction of said water movement as shown at 10^a.

It will be understood that the vacuum fuel feed device has the usual or any convenient and suitable means for alternating the dominance of atmospheric pressure and suction in the vacuum chamber, said vacuum chamber being provided with an atmosphere inlet shown at 9, through which atmospheric pressure is admitted to the chamber. The particular means for alternating the dominance of atmospheric pressure and suction shown 80 consists of the familiar snap action device controlling the valves, 12 and 13, which seat respectively at the suction port and the atmosphere inlet port, said device being actuated by the float, 15, according to the level of liquid fuel in the vacuum chamber, in a manner well understood and requiring no further or more specific description. 85 90 95

Incidentally a certain advantage is derived from the expedient described for producing the partial vacuum, consisting in that the air drawn from the vacuum chamber by the entrainment in the Venturi throat piece 100 serves to aerate the cooling water to a certain extent, and the air thus supplied to the cooling water escaping in the radiator carries off a somewhat larger amount of heat that would otherwise be radiated, thus assisting in the cooling by the circulation of the cooling water. Inasmuch as the air thus drawn into the cooling water is drawn from the vacuum chamber where it may be somewhat charged at times with fuel vapor, it 105 110 may be thought advisable to provide for preventing this air, when it escapes from the

radiator, from passing out freely into the atmosphere where in extreme cases, it might cause a noticeable odor of gasoline vapor, or even be inflammable. To meet this possible objection a tube, 20, may lead from the upper part of the radiator above the surface of the cooling water therein into the exhaust pipe, 21, discharging therein in the direction of onward movement of the exhaust gases therethrough, so that the gasoline-vapor-charged air may pass off with exhaust gases.

Fig. 3 indicates how the entrainment of air for producing partial vacuum in the chamber, 6, may be secured from the oil circulatory system, if preferred. By interposing in the oil feed line, 16, a Venturi throat-way, 10^x, (perhaps best located adjacent the circulating pump, 16^a), the flow of oil will 20 create a suction in pipe, 11^x, which opens in the direction of flow at a point of low pressure in the venturi, 10^x.

I claim:

1. In combination with an internal combustion engine, a vacuum fuel feed device comprising a low level main fuel tank, a fuel feed tank at a higher level, and a conduit from the lower to the higher tank; the higher tank comprising a vacuum chamber 30 and a reservoir into which the chamber dis-

charges fuel, a Venturi throat piece interposed in a liquid circulatory system of the engine, and an air pipe leading from the top of the vacuum chamber to said Venturi throat, whereby a partial vacuum is produced in the vacuum chamber by the entrainment action of the liquid circulating current; the vacuum chamber having a pressure inlet and means for alternating in said chamber the dominance of the suction and the pressure derived through such inlet.

2. In a construction such as set out in claim 1 foregoing, the air pipe for connecting the venturi with the vacuum chamber being extended into the Venturi pipe and 45 projecting forward therein beyond the apex or point of greatest restriction of the venturi.

3. In a construction such as set out in claim 1, the liquid circulatory system utilized being the cooling water system, a pipe leading from the upper part of the radiator, opening into the engine exhaust pipe and projecting therein in the direction of the exhaust movement therethrough for the purpose indicated.

In testimony whereof I have hereunto set my hand at Chicago, Illinois, this 12th day of December, 1917.

WEBB JAY.
